UNITED STATES PATENT OFFICE.

EDWIN A. KING, OF PHILADELPHIA, PENNSYLVANIA.

CALORIFIC KILN.

No. 900,742.

Specification of Letters Patent.

Patented Oct. 13, 1908.

Application filed October 15, 1907. Serial No. 397,585.

To all whom it may concern:

Be it known that I, EDWIN A. KING, a citizen of the United States, residing at the city of Philadelphia, in the county of Philadelphia and State of Pennsylvania, have invented certain new and useful Improvements in Calorific Kilns, of which the following is a specification.

My invention relates to certain improvements in kilns such as described and shown in Letters Patent No. 803,326 granted to me under date of October 31st 1905; and in such connection my present invention relates more particularly to the constructive arrangement of air-flues, furnace-flues and means for controlling the inlet of air into the air-flues so as to permit first of the conducting of heat from the furnace to any portion of the products to be burned in the kiln, in which needed and to prevent the conduct of heat to other portions of the products where not needed, so as to more thoroughly equalize inequality of conditions in the burning of said products in the kiln; second to so arrange the kiln for the defined purpose as to be able to conduct at will heat and flame throughout the entire length of the arches formed by clay products or up to any portion in their length to insure uniformity of burning of the such products in the kiln; third to locate the air-outlet of the air-flues instead of at the beginning of the branch furnace-flues as in the said patent, in the present kiln substantially midway of the same so as to dispense with a recombustion chamber and so as also to insure combustion of equal portions of the products of combustion with equal proportions of heat from the furnace chamber conveyed directly into each of the branch flues and prior to entrance of the same into arches of the kiln; fourth to dispense with the dampers of the patent, in the branch furnace-flues and to provide the air-flues of each of the branch flues with slides to control the entrance of air in each of the air-flues at the inlet thereof so as to permit without the aid of dampers of the unequal entrance of heat and products of combustion into certain of the branch flues and thus into the arches communicating with the flues; fifth to obtain by controlling the entrance of air into the furnace-flues of an increase in draft in certain of these flues and thus of a suction action which permits of the entrance of the entire products of combustion of the furnace or a portion there-

of, into one of the furnace-flues and to arches communicating therewith; and sixth to provide the furnace with two sets of observation or peep holes, one set above each of the sets of air-flues and to locate the same in the vertical central axis of the arches to permit of the ascertaining of the action of heat and flame on clay products throughout the entire cross-section of the arch.

The nature and scope of my invention will be more fully understood from the following description taken in connection with the accompanying drawings forming part hereof, in which

Figure 1 is a top plan view of the kiln, partly in elevation and partly in section. Fig. 2 is a front elevational view thereof. Figs. 3 and 4 are longitudinal vertical sectional views of a portion of the kiln and one of the furnaces thereof. Fig. 5 is a cross-sectional view of the furnaces, and Fig. 6 is a perspective view of a portion of the kiln and one of the furnaces thereof.

Referring to the drawings, 8 represents an updraft calorific kiln of usual construction, from each of the end walls 9 of which extend in the present instance, two furnaces 10. As shown in Figs. 1 and 3, the fire-chamber 11, of the furnace 10, communicates with partially triangularly shaped or converging flues 14 and 15, elevated above the grate 12, of the fire chamber 11, the apex or meeting portion 16, of the inner walls of the flues 14 and 15, are arranged directly in the vertical central axis of the fire chamber 11, and the purpose of the same is to evenly distribute the heat and products of combustion coming from the fire chamber 11, by parting the same in striking the apex 16, and conducting an equal portion of the heat and products of combustion into each of the flues 14 and 15. These converging flues at their outwardly flaring ends are deflected into straight portions 18, to be in alinement with the arches not shown, which are built in the clay products to be burned in the kiln 8. The elevation 19, separating the flues 14 and 15 from the fire-chamber 11, forms a bridge-wall which prevents the fuel from entering these flues and producing an uneven distribution of the heat and products of combustion in the arches of the kiln.

In order to insure complete combustion of the equal portion of the products of combustion of the furnace 11, entering each of the flues 14 and 15, and prior to their entering

into the arches of the kiln 8, there are provided two air-flues 20 and 21, one above the other at each side of the fire chamber 11. The lower flues 21 are arranged below the 5 level of the base of the furnace flues 14 and 15 and are inwardly and then upwardly deflected and terminate with their outlets 22 substantially in the central portion of the furnace flues 14 and 15. The upper flues 20, 10 are arranged in alinement with the base of the furnace flues and the floor 23 of the kiln 8 and likewise terminate in the central portion of the flues 14 and 15, but owing to the converging outer walls of these flues extend up 15 to the straight portion 18 of the same. As the air-flues are separated from the fire-chamber 11 by a comparatively thin wall of fire brick 24, and as the air enters the flues at the front wall of the furnace 10, the same is 20 gradually conducted from the coldest to the hottest portion of the furnace and by passing partially through the highly heated bridge-wall 19, and by being delivered at a point in alinement with the level of the bridge wall, 25 the air will be heated to a temperature corresponding to that of the heat generated in the fire-chamber 11. The highly heated air rising in the furnace flues 14 and 15, will commingle with the flame and products of combustion of the unconsumed products of combustion entering the same in equal portions and will insure complete consumption of these unconsumed products prior to introduction into the arches of clay product in the 30 kiln 8. By the even distribution of the heat and products of combustion of each of the furnaces 10 of the kiln to two arches of clay products, each arch in the kiln is supplied with an equal quantity of heat and consequently 35 the clay products if evenly spaced or built up in the kiln, will be uniformly burned throughout, as each arch will diffuse an equal amount of heat through the mass of clay products built upon and surrounding the 40 arch. However, the placing or even spacing of the clay products in the kiln from each other is seldom attended with any degree of regularity and consequently in certain portions of the kiln they are placed closer together 45 than other portions thereof. The result being an uneven burning of the clay products in the kiln 8, even if each of the arches is supplied with an equal amount of heat and products of combustion.

50 To equalize the uneven burning of the clay products and to insure uniformity in the burning, the heat and products of combustion of the furnaces 10 must be conducted to portions in the kiln in which the same are needed and must also be prevented from being conducted to other portions where the heat is not needed. This is accomplished in 55 the following manner. As shown in Fig. 6, each of the furnaces 10, of the kiln 8, is provided with guides 28 which serve to support

slides 29 by means of which the air-flues 20 and 21 may be wholly or partially closed. If it has been determined that the clay-products in the arch, for instance opposite the furnace flues 15, have not advanced as far in their 60 burning as those in the arch adjacent thereto and opposite to the flues 14, the air flues 20 and 21, leading to the furnace flue 14, are closed by the slides 29 at both sides of the kiln 8 while the air flues 20 and 21, for the 65 furnace flues 15, remain open. Air will thus only enter the flues 15 and by draft and the suction action thus formed in these flues, all the heat and the entire unconsumed products of combustion of the furnaces 10, at both 70 ends of the kiln 8, will be drawn into the flues 15, and consumed therein, and the flame of these products will enter the arch communicating with the furnace flues 15 from opposite sides of the kiln and will meet each other 75 about midway in this arch. If both sets of air-flues 20 and 21 are closed for instance at the right hand side of the kiln in Fig. 1, and only the air flues leading to the furnace flue 15 at the left hand side of the kiln remain 80 open, the flame will be conducted in a direction from left to right in Fig. 1, throughout the length of the arch communicating with the furnace-flues 15. Or if the air-flues 20 and 21, leading to the furnace flue 15, are 85 partially closed at the right hand side of the kiln 8, in Fig. 1, and entirely open on the left hand side thereof, the flame will pass up to a certain portion in the arch communicating with the flues 15. By the shifting of the 90 slides 29, the entrance of air into the flues 20 and 21, at one or the other side of the furnaces 10, can readily be regulated and by this regulation and the more or less strong draft and suction action produced in the 95 furnace flues the entire heat or a portion thereof, as well as the entire or a portion of the products of combustion, can be at will conducted to any portion of the clay products and be prevented from reaching other 100 portions thereof, and thus a regulation and a uniformity in the burning of the clay products thereby always insured.

In order to permit of the ready observation of the burning of clay-products in the 105 kiln 8, each of the furnaces 10, thereof, is provided with observation or peep holes 30 and 31, arranged one above the other and above each set of air-flues 20 and 21, and in the central vertical axis of the arches of clay 110 products, not shown. As shown in Fig. 4, the lower peep holes 31, terminate respectively, in the furnace flues 14 and 15, while the upper holes 30, also extend through the end walls 9, of the kiln 8, and terminate opposite the upper portion of the arches, not shown, communicating with the furnace-flues. By this arrangement of peep holes, 115 the arches throughout their entire length and throughout their entire cross-section are 120

125 130

readily visible, to thus permit of the ascertaining of the action of heat and flame in any part of the arches. Each of the peep holes 30 and 31 is normally closed by a cover 32 pivotally secured in the point 33 to the respective furnaces 10, so as to be held by gravity in their operative position. A stop 34 arranged adjacent to each of the covers 32, serve as a rest for the same when the 10 cover is lifted to free the peep-hole controlled by the lifted cover, as shown in Fig. 6.

In order to prevent partial closing of the air-flues 20 and 21 by the sliding door 35 of the furnaces 10 when the same are shifted to 15 free the inlet 36 to the fire chamber 11, the air-flues are outwardly deflected at 38, at the front or inlet portion, as shown in Figs. 1, 2 and 6.

Having thus described the nature and objects of my invention what I claim as new 20 and desire to secure by Letters Patent is:—

1. The combination with a calorific kiln having a floor with a fire-chamber formed as an extension of the front walls and with furnace-flues in the front walls in alinement with the floor and arranged to equally divide heat and products of combustion from said chamber prior to entrance into said flues, of air-flues at each side of said fire-chambers in 25 alinement with said furnace-flues and directly terminating therein and means to control the inlet of air in said air-flues so that 30 35 40 45 50 55

through partial or complete closing of certain of said flues is adapted to be deflected by increasing or decreasing the draft, the greater part or entire portion of the heat and flames of said furnace-chamber into one of said furnace-flues.

2. The combination with a calorific kiln having a floor with a fire-chamber formed as an extension of the front walls and with furnace-flues in the front walls in alinement with the floor and arranged to equally divide heat and products of combustion from said chamber prior to entrance into said flues, of air-flues at each side of said fire-chambers in alinement with said furnace-flues and directly terminating therein and means to control the inlet of air in said air-flues so that through partial or complete closing of certain of said flues, oppositely arranged, to conduct by increasing or decreasing the draft, the greater part or entire portion of the heat and flames of one of said fire-chambers into one of said furnace-flues up to a certain portion or throughout the entire length of the arches of clay products.

In witness whereof, I have hereunto set my signature in the presence of two subscribing witnesses.

EDWIN A. KING.
